UNITED STATES PATENT OFFICE.

PAUL PIGNOT, OF YONKERS, NEW YORK, ASSIGNOR TO ALEXANDER SMITH & SONS CARPET COMPANY, OF SAME PLACE.

DESIGN FOR A CARPET.

SPECIFICATION forming part of Design No. 14,033, dated July 3, 1883.

Application filed May 4, 1883. Term of patent 3½ years.

To all whom it may concern:

Be it known that I, PAUL PIGNOT, of Yonkers, Westchester county, and State of New York, have invented a new and original Design for Carpets, of which the following is a specification.

The accompanying photograph illustrates my new design for carpets.

This invention relates to a new design for carpets, oil-cloths, and analogous fabrics; and it consists of the new ornamentation of parts hereinafter more fully pointed out.

A is a spray of darkly-shaded flowers, and

B a spray of lighter-shaded flowers, both of these sprays being placed in juxtaposition on the plain background of the carpet, as shown, thereby producing the faint and delicate design which is represented on the photograph.

I claim—

The design for carpets, consisting of the figures A and B, substantially as shown.

PAUL PIGNOT.
